Primary Examiner—Freda Nunn
Attorney, Agent, or Firm—Woodcock Washburn Kurtz Mackiewicz & Norris

[57] **CLAIM**

The ornamental design for a memory device, as shown and described.

DESCRIPTION

FIG. 1 is a perspective view of a memory device incorporating our new design;

FIG. 2 is a front elevational view;

FIG. 3 is a rear elevational view;

FIG. 4 is a first side elevational view;

FIG. 5 is a second side elevational view;

FIG. 6 is a top plan view; and,

FIG. 7 is a bottom plan view.

The broken lines are shown in the views for illustrative purposes only and form no part of the claimed design.
